UNITED STATES PATENT OFFICE.

GEORGE A. WEIDELY, OF INDIANAPOLIS, INDIANA.

RADIATOR-MOUNTING FOR AUTOMOBILES.

1,254,181.

Specification of Letters Patent. Patented Jan. 22, 1918.

Application filed November 22, 1913. Serial No. 802,876.

To all whom it may concern:

Be it known that I, GEORGE A. WEIDELY, a citizen of the United States, residing at Indianapolis, in the county of Marion and 5 State of Indiana, have invented a new and useful Radiator-Mounting for Automobiles, of which the following is a specification.

It has heretofore been customary, in mounting radiators for internal combustion 10 engines in automobiles, to support the radiator upon the chassis frame and connect the induction and eduction passages thereof by flexible connections with the water spaces of the engine. Such a construction results 15 in many disadvantages and the object of my present invention is to avoid these difficulties by separating the radiator from the chassis frame and connecting it directly to the engine so that permanent and rigid connections may be made whereby the radiator 20 will partake of the various vibrations of the engine.

The accompanying drawings illustrate my invention. Figure 1 is a side elevation in 25 partial vertical section of an engine having its radiator mounted in my improved manner; Fig. 2 a fragmentary front elevation showing the chassis frame in transverse section.

30 In the drawings, 10 indicates the chassis frame and 11 indicates the engine frame or main body connected at its forward end to the frame 10 by means of bolts 13. The exact manner of connection of the engine 35 body with the chassis frame is immaterial.

Projected from the lower part of the water space of the engine 11 is a shelf 14 beneath which is an extension 15 of the lower 40 part of the water space of engine 11 and to this shelf I directly bolt the bottom of the radiator 16 by any suitable means, such, for instance, as the bolts 17, and to the chamber 15 is connected the usual circulat-

ing pump 18 of any desired type. Attached to the induction opening 19 of the water 45 chamber of the engine is a hollow standard or fitting 21 provided at its upper end with a plate 22 by means of which the upper end of the radiator 16 may be attached to the bracket 21, said bracket thus forming a support for the upper end of the radiator as 50 well as a water connection for the flow of the heated water from the engine to the radiator.

By this arrangement, the radiator may be 55 firmly bolted in place yet may be readily detached from the engine, the shelf 14 being attached to the engine by readily accessible bolts 23 and the hollow standard 21 being similarly attached to the engine body 60 by the readily accessible bolts 24.

I claim as my invention:

The combination, in a motor vehicle, of a main frame, an internal combustion engine carried by the main frame and provided with a water chamber having induction and eduction openings, a chambered shelf associated with the induction openings of the engine water chamber, a radiator supported upon said shelf and having its 65 eduction opening associated with the chamber of said shelf, and a tubular bracket forming a connection between the induction opening of the radiator and the eduction opening of the engine water chamber, said 70 tubular bracket supporting the upper end of the radiator.

In witness whereof, I have hereunto set my hand at Indianapolis, Indiana, this 11th day of November, A. D. one thousand nine 80 hundred and thirteen.

GEORGE A. WEIDELY.
